United States Patent Office

Des. 176,895
Patented Feb. 14, 1956

176,895

COMBINATION WINE BOTTLE COOLER, ICE OR BEVERAGE BUCKET AND HOLDER THEREFOR

Joseph N. Amigone, Buffalo, N. Y.

Application May 16, 1955, Serial No. 36,023

Term of patent 14 years

(Cl. D58—17)

Fig. 1

Fig. 2

Fig. 1 is a top plan view of a combination wine bottle cooler, ice or beverage bucket and holder therefor showing my new design; and

Fig. 2 is a view thereof in front elevation.

This application is a continuation-in-part of my copending application Serial No. D. 30,356, filed May 6, 1954.

I claim:

The ornamental design for a combination wine bottle cooler, ice or beverage bucket and holder therefor, as shown.
